UNITED STATES PATENT OFFICE.

GEORGE B. NICHOLS, OF GALVESTON, TEXAS.

LUMBER-DOOR FOR RAILROAD BOX-CARS.

SPECIFICATION forming part of Letters Patent No. 280,395, dated July 3, 1883.

Application filed December 6, 1882. (No model.)

To all whom it may concern:

Be it known that I, GEORGE B. NICHOLS, of Galveston, in the county of Galveston and State of Texas, have invented a new and useful Improvement in Lumber-Doors for Railroad Box-Cars; and I do hereby declare the following to be a full, clear, and exact description thereof.

My invention relates to an improvement in railroad-cars; and it consists in a lumber-door situated at one end of the car and provided with devices for preventing rain, snow, or sparks from entering through the space above the door.

Box-cars are often shipped from one point to another loaded with merchandise and returned empty, when they could be loaded with lumber on the return-trip were it not that lumber cannot be put in box-cars through the side doors. To enable this difficulty to be obviated and permit of the loading of box-cars with lumber, I form a doorway in the end of the car through which the lumber is easily loaded and unloaded from the car, said doorway being closed by a door and weather-shutter, as will hereinafter more fully appear.

I will now describe my invention so that others skilled in the art may manufacture and use the same, reference being had to the accompanying drawings, forming a part of this specification, in which—

Figure 1 is a front elevation of the end of the car, showing the door. Fig. 2 is a rear elevation of the same. Fig. 3 is a longitudinal section of the door and end of the car, and Fig. 4 is a front elevation of a part of the same.

Like letters refer to like parts wherever they occur.

In the end of the car is a doorway, *k*, of sufficient size to allow of lumber being passed through the same into the car.

On each side of the doorway *k*, on the outside of the car, are strips *k'*, which form ways *k²*, in which the door *E* slides up and down, so as to close and open the doorway *k*.

At the lower end of the doorway *k* is a sill, *G*, upon and against which the lower end of the door rests when shut. Passing through the sill *G* is a bolt, *H*, around which is a spiral spring, *I*, the ends of which spring bear against a plate, *L*, on the inner face of the sill *G*, and a pin, *h*, which passes through the bolt *H*.

At the lower end of the door *E*, on the outer face thereof, is a catch or handle, *F*, the inner face of which is recessed for the reception of the end of the bolt *H*, which passes into the recess through a hole or slot in the door *E*. Below this handle *F*, and projecting therefrom, is a lug, *f*, having an inclined face, *f'*.

Secured to the inner face of the end of the car, at the top of the doorway *k*, is a casing, *D*, in which is pivoted or hinged, by a rod, *B*, a shutter, *A*. This rod *B* is secured to the shutter beyond the middle portion thereof, so that by the force of gravity the shutter will tend to assume a perpendicular position. The leaf or part *A'* of the shutter, being heavier than the part *A²*, falls down upon and extends over the top edge of the door *E*, while the small part or leaf *A²* rises and comes in contact with the weather-strip *C*, which is attached to and extends down from the upper portion of the casing *D*. When the door is opened it lifts the shutter *A*, which turns on its axis *B* in the casing *D* and allows the passage of the door without interfering with the movement of the same. When the car has been loaded, the door is shut by releasing the same, and it falls of its own weight, or is drawn down. The inclined plane *f'* on the lug *f* strikes the end of the spring-bolt *H*, pushing it in, so as to allow the end of the door to pass the same and rest on the sill *G*. The end of the bolt *H*, then being opposite the recess *F*, is released and passes into the recess, being moved by the spring *I*, thereby locking the door automatically in such a manner that it can only be unlocked from the inside of the car by withdrawing the bolt *H* from the recess *F*. The shutter *A*, resting on and over the top end of the door, effectually prevents any water or sparks from entering the car between the top of the door and the doorway, and the portion *A²* of the shutter bearing against the strip *C* makes a tight joint at that point.

The advantages of my invention are the saving of time and labor by the easy transportation of lumber in box-cars; and as my improved door is perfectly tight it does not injure the car for the purpose of the transportation of other merchandise.

I am aware that a sliding door for box-cars has heretofore been provided with a movable

weather and fire strip pivoted on the rear end of the door to swing across and close the crack between the door and car when the door was closed, and do not herein claim, broadly, the combination of a sliding door and pivoted strip; but,

Having thus described my invention, what I claim, and desire to secure by Letters Patent, is—

10 1. In a box-car, the combination, with the end thereof, of a vertically-sliding door and a shutter pivoted above the door, substantially as and for the purpose specified.

15 2. In a box-car, the combination of a vertically-sliding door and an overbalanced shutter pivoted in the frame above the door and actuated thereby, substantially as and for the purpose specified.

20 3. In a box-car, the combination of a sliding door provided with a lifting-catch having a recess and an inclined face, with a spring-bolt arranged on the inner face of the door-frame, substantially as and for the purpose specified.

25 4. In a box-car, the combination, with a vertically-sliding door, of an overbalanced shutter pivoted above the door, and a spark and weather strip secured to the door-frame above

the pivoted shutter, substantially as and for the purpose specified.

5. The combination, with a sliding door, of an overbalanced shutter pivoted on the door-frame in the path of the sliding door, substantially as and for the purpose specified.

6. The combination, with a sliding door, of a shutter pivoted on the door-frame in the path of the sliding door, and a weather and fire strip secured to the door-frame and extending partially over the pivoted shutter, substantially as and for the purpose specified.

7. The combination of the sliding door, an overbalanced shutter pivoted on the door-frame and actuated by the door, a weather-strip secured to the door-frame and extending partially over the shutter, and a shutter-casing which extends over the weather-strip and shutter, substantially as and for the purposes specified.

In testimony whereof I have hereunto set my hand this 28th day of November, A. D. 1882.

GEORGE B. NICHOLS.
